CLAIM

The ornamental design for a sheet trimmer, as shown and described.

DESCRIPTION

FIG. 1 is a perspective view of a sheet trimmer showing our new design,

FIG. 2 is a top plan view of the sheet trimmer shown in FIG. 1,

FIG. 3 is a front elevational view of the sheet trimmer shown in FIG. 1,

FIG. 4 is a bottom plan view of the sheet trimmer shown in FIG. 1,

FIG. 5 is a rear plan view of the sheet trimmer shown in FIG. 1,

FIG. 6 is a side elevational view of the sheet trimmer shown in FIG. 1; and,

FIG. 7 is a perspective view of the sheet trimmer shown in FIG. 1 showing the sheet guide in the extended position.

The broken lines including the calibrations are in no way intended to form part of the claimed design and are for illustrative purposes only.
